(56) **References Cited****DESCRIPTION**

The present application is also related to U.S. Design patent application Ser. No. 29/554,962 (now D832,454), also entitled Sample Container Rack and filed on Feb. 17, 2016, as well as U.S. Design patent application Ser. No. 29/554, 966 (now D836,794), also entitled Sample Container Rack and filed on Feb. 17, 2016, the disclosures all of which are incorporated herein by reference.

FIG. 1 is a front perspective view of a sample container rack according to our design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines illustrate unclaimed environmental structure and form no part of the claimed design. The dash-dot-lines are boundary lines that form no part of the claimed design.
